A. MUNGENAST.

LEVER EXTENSION.

APPLICATION FILED JAN. 30, 1919.

Patented July 8, 1919.

INVENTOR:-

Andrew Mungenast

John C. Higdon

ATTORNEY.

UNITED STATES PATENT OFFICE.

ANDREW MUNGENAST, OF ST. LOUIS, MISSOURI.

LEVER EXTENSION.

1,308,990.

Specification of Letters Patent.

Patented July 8, 1919.

Application filed January 30, 1919. Serial No. 274,044.

To all whom it may concern:

Be it known that I, ANDREW MUNGENAST, a citizen of the United States, residing at St. Louis, in the State of Missouri, have invented certain new and useful Improvements in Lever Extensions, of which the following is a specification containing a full, clear, and exact description, reference being had to the accompanying drawings, forming a part hereof.

My invention relates to an improved lever extension, and it consists in the novel construction and combination of parts hereinafter fully described and particularly claimed.

The object of my invention is to provide an improved lever-extension that is especially capable of quick application to the hand-brake lever of the Ford automobile, as well as to all other levers which are located in such a position that the operator is compelled to stoop forward (and thereby take his eyes off of the road ahead of the car) in order to grasp the lever in making an emergency stop; whereby the heretofore inaccessible hand-levers of this kind will be rendered accessible without stooping forward, and the safety of the driver or operator (as well as of the passengers) will be made more secure.

In the drawings,

Figure 1 is a top plan view of my present form of lever-extension attachment, ready to be applied to the Ford automobile hand-lever.

Fig. 2 is a side-elevation of same, as it appears when applied to the automobile hand-lever, and

Fig. 3 is a side-elevation of a modification, to be used as a permanent and integral extension of the hand-lever.

The numeral 1 designates the main body of the hand-lever which is to be extended into a convenient position, as shown in Fig. 2.

The hand-lever 1, as heretofore and now manufactured and used, is provided with the well known "grip" portion 2 at its free end, below which is pivoted at 3 the usual pawl-lifting lever 4, having the upper end of the common pawl-lifting rod 5 pivoted at 6 to it; whereby, when said pawl-lifting lever is forced toward said grip portion of the pawl (not shown) will be lifted out of engagement with the teeth of the holding-

sector (not shown), and the lever 1 may be moved to apply or release the brakes.

The numeral 7 designates my base casting for the grip-clamp, which is detachably secured upon the said grip portion 2 of the hand-lever 1 by means of a clamping-plate 8 that is curved to fit the curve of the said grip portion, and provided at its opposite edges with perforated flanges, the perforations of which register with like perforations formed in mating flanges on the edges of the said clamping-plate 8, and suitable bolts or common screws 9 are passed through the registering perforations of both base-casting and clamping-plate, to securely but detachably hold the base-casting upon said grip portion of the hand-lever.

At the upper end of said base-casting 7 is an integral bifurcated extension 10, and a substantially horizontal lever-extension 12 has one of its ends pivotally mounted in the fork or bifurcation of said base-casting upon a common bolt or rivet 11, whereby the opposite end of the said lever extension may be moved freely up and down a limited distance, determined by contact of the lever with the bottom wall of the said bifurcation, as indicated by the dotted lines shown in Fig. 2.

The free (or rear) end of said lever-extension 12 is provided with a suitable handle or hand-hold, which (in the present case) is shown in the form of an integral downward and forward curved portion 13, and which may be grasped by the operator in much the same way that he would grasp a common curved cane-handle or umbrella-handle; which he does in pulling the lever 1 back, or in pushing it forward, and in both cases this movement can be readily accomplished without stooping toward the lever, even though it be located a considerable distance in front of the operator, and so far down that (if my lever-extension were not attached) he would have to stoop forward in order to reach the grip portion 2 of the hand-lever.

In order to also reach the pawl-lifting lever 4, at the same time, without stooping forward I provide opposite clamping-jaws 14 and 15 with opposite mating perforated side-flanges, secured in position upon the upper end of the said pawl-lifting lever by means of common bolts or screws 16, the rear jaw 15 having a rearwardly-extending

integral arm 18 in which is an internally threaded socket.

Fixed in said threaded socket of said arm 18 is the forward end of a horizontal pawl-lifting lever-extension 17, the rear portion of which passes loosely through a bearing 19 formed in the upper portion of the said handle 13 of the said lever-extension 12, and projects conveniently to carry a suitable 10 push-button 20.

A coiled spring 21 is mounted upon the said pawl-lifting lever-extension or rod 17 between said button 20 and the said handle 13, to normally hold said rod at the 15 limit of its outward movement, as well as to assist the usual spring of the pawl-lifting lever.

In the modification shown in Fig. 3, the lever-extension 12 is shown as an integral 20 part of the hand-lever 1, and the pawl-lift- 25 ing lever 4 is pivoted conveniently near the handle 13 upon the said lever-extension, while the pawl-lifting rod 5 is also provided with an integral extension which is curved rearwardly to the point at which its rear end is pivotally connected to the pawl-lifting lever 4, the button 20 and coiled-spring 21

being dispensed with, and the usual pawl-lifting lever flat spring 23 being used to return the parts to their normal position. 30

A suitable guide or bearing 22 on the hand-lever holds the said pawl-lifting rod 5 in proper relation to the said lever during operation.

The operation of my invention will be 35 clear without further description.

I claim:—

An extension attachment for automobile hand-levers, comprising a clamping-device adapted to fit the end of a sand-lever, a 40 rearwardly-extending member pivoted at its front end to the said clamping-device, and having a handle at its free rear end, and a pawl-operating member having a clamp adapted to fit the pawl-latch lever of said 45 hand-lever.

In testimony whereof I have signed my name to this specification in presence of two subscribing witnesses.

ANDREW MUNGENAST.
